UNITED STATES PATENT OFFICE.

WILLIAM L. BEAN, OF WEST HAVEN, CONNECTICUT.

LOCOMOTIVE-SMOKE-BOX STRUCTURE.

Application filed March 31, 1925. Serial No. 19,618.

To all whom it may concern:

Be it known that I, WILLIAM L. BEAN, a citizen of the United States, and a resident of West Haven, in the county of New Haven and State of Connecticut, have invented an Improvement in Locomotive-Smoke-Box Structures, of which the following description, in connection with the accompanying drawings, is a specification, like characters on the drawings representing like parts.

This invention relates to a novel locomotive smoke-box structure, and will be best understood by reference to the following description, when taken in connection with the accompanying drawings of one specific embodiment thereof, while its scope will be more particularly pointed out in the appended claims.

In the drawings:

Fig. 1 is a central, vertical, longitudinal section of a locomotive smoke-box structure exemplifying the invention;

Fig. 2 is a sectional view on an enlarged scale on line 2—2 of Fig. 1; and

Fig. 3 is a sectional view on line 3—3 of Fig. 1.

Referring to the drawings, and to the embodiment of the invention which is selected for exemplification, the smoke-box, instead of being built up of sheet metal and other fabricated shapes, as is now the common practice, is composed of a plurality of cast metal sections, herein two complementary castings 4 and 5, and these sections, in the present instance, abut along lines extending lengthwise of the smoke-box, herein in a horizontal plane A. The upper section presents a smoke-stack opening 6, and the lower section presents an exhaust nozzle opening 7, the latter extending through a base 8, for attachment to a usual cylinder saddle not shown herein. The upper and lower sections present flanges 9 and 10, best shown in Fig. 2, along opposite sides of the smoke-box, for the attachment of the sections to each other by appropriate fastening elements, herein bolts 11, which extend through the flanges and are provided with nuts 12 to draw the flanges together. In the present example, the flanges and their abutments are on the interior of the smoke-box, where they are out of the way and are not exposed to the elements. The external surface is thus left perfectly smooth.

In the present example, one of the sections, herein the lower section, presents a

recess 13, which receives a projection 14 presented by the upper section. These interfitting parts position the sections with relation to each other. One of the flanges, herein in the flange 10, presents a shallow recess or depression 15, the effect of which is to cause the clamping pressure to be concentrated along two narrow surfaces between which the clamping bolts are situated. By this means, a tight joint is easily obtained.

One of the complementary castings, herein in the upper section 4, presents integral steam pipes 16, having passages 17 from the interior to the exterior of the smoke-box. Each of these pipes in the present example is formed partly within and partly without the smoke-box. Its internal and external portions present seats 18 and 19, herein beveled or chamfered to receive correspondingly shaped surfaces of the internal and external surfaces of the steam pipes which are to be attached thereto, while flanges 20 and 21 are provided for the attachment of the usual steam pipes by studs, not shown, threaded into the flanges. About the external portions of the steam pipes, the casting presents an integral flange 22 for the convenient attachment of the usual lagging and jacketing about the external portion of the steam piping.

Referring again to Fig. 1, the complementary castings in the present example are provided with integral projections 23 and 24, which together constitute a support for a generally upright deflector of any appropriate construction, not shown herein. The lower section is provided with a similar integrally formed projection 25 for a generally horizontal deflector of any appropriate construction, not shown herein. Similarly, the upper and lower castings are provided with integral projections 26 and 27, which together constitute a support for any appropriate spark-netting, not shown herein.

Having thus described one embodiment of the invention, but without limiting myself thereto, what I claim and desire by Letters Patent to secure is:

1. A locomotive smoke-box structure comprising, in combination, two complementary castings abutting in a plane extending lengthwise of the smoke-box structure, and fastening elements securing said castings together.

2. A locomotive smoke-box structure comprising, in combination, two complementary

castings abutting in a plane extending lengthwise of the smoke-box structure, said castings presenting flanges, and fastening elements securing said flanges together.

5. A locomotive smoke-box structure comprising, in combination, two complementary castings abutting in a plane extending lengthwise of the smoke-box structure, one of said castings presenting a smoke-stack opening and the other an exhaust nozzle opening, and fastening elements which force the abutting surfaces of said castings together.

10. A locomotive smoke-box structure comprising, in combination, two complementary castings abutting in a plane extending lengthwise of the smoke-box structure, one of said castings presenting a base for attachment to a cylinder saddle, and fastening elements which secure said castings together.

15. A locomotive smoke-box comprising, in combination, a plurality of complementary cast sections abutting along lines extending lengthwise of the smoke-box, and means to secure said sections together.

20. A locomotive smoke-box comprising, in combination, a plurality of complementary cast sections abutting along lines extending lengthwise of the smoke-box, said sections being provided with integral flanges, and means to secure the flanges of one section to the flanges of another section.

25. A locomotive smoke-box structure comprising, in combination, an upper and a lower section abutting in a plane containing the longitudinal axis of the smoke-box structure, said sections presenting flanges, and bolts extending through said flanges and securing said sections together.

30. A locomotive smoke-box structure comprising, in combination, an upper and a lower section abutting in a plane extending lengthwise of the smoke-box structure, said sections presenting internal flanges, and fastening elements extending through said flanges and securing said sections together.

35. A locomotive smoke-box structure comprising, in combination, an upper and a lower section abutting in a plane extending lengthwise of the smoke-box structure, one of said sections presenting flanges abutting in a plane extending lengthwise of the smoke-box structure, and fastening elements securing said flanges together.

40. A locomotive smoke-box structure comprising, in combination, an upper and a lower section abutting along lines extending lengthwise of the smoke-box structure, one of said sections presenting a recess and the other a projection received in said recess to position said sections with relation to each other, and means to secure said sections together.

45. A locomotive smoke-box structure comprising, in combination, an upper and a lower section abutting along lines extending lengthwise of the smoke-box, one of said sections presenting a recess and the other a projection received in said recess to position said sections with relation to each other, and means to secure said sections together.

50. A locomotive smoke-box comprising, in combination, a plurality of complementary castings abutting along lines extending lengthwise of the smoke-box, said castings having integral internal projections presenting deflector supports.

55. A locomotive smoke-box comprising, in combination, a plurality of complementary castings abutting along lines extending longitudinally of the smoke-box, said castings having integral complementary projecting portions presenting deflector and spark-netting supports.

60. A locomotive smoke-box structure comprising, in combination, two complementary castings abutting in a plane extending lengthwise of the smoke-box structure, one of said castings presenting integral steam pipes having passages from the interior to the exterior.

65. A locomotive smoke-box structure comprising, in combination, upper and lower complementary castings, said upper casting presenting integral steam pipes having passages from the interior to the exterior.

70. A locomotive smoke-box structure comprising, in combination, upper and lower complementary castings, said upper casting presenting integral, laterally disposed steam pipes having passages from the interior to the exterior.

75. In testimony whereof, I have signed my name to this specification.

WILLIAM L. BEAN.
